UNITED STATES PATENT OFFICE.

ADOLPH PEDERSEN, OF CLEVELAND, OHIO, ASSIGNOR TO THE VAN DORN-ELLIOTT ELECTRIC COMPANY, OF CLEVELAND, OHIO, A CORPORATION OF OHIO.

MOTOR-CONTROLLER.

No. 809,460.

Specification of Letters Patent.

Patented Jan. 9, 1906.

Application filed May 26, 1905. Serial No. 262,368.

To all whom it may concern:

Be it known that I, ADOLPH PEDERSEN, a citizen of the United States, and a resident of Cleveland, county of Cuyahoga, and State of Ohio, have invented a new and useful Improvement in Motor-Controllers, of which the following is a specification, the principle of the invention being herein explained and the best mode in which I have contemplated applying that principle, so as to distinguish it from other inventions.

My invention relates to controlling mechanism, and especially to such mechanism as is adapted to control the motors used in electrically - operated portable drills and other electrically-driven tools and machines.

Said invention consists of means hereinafter fully described, and specifically set forth in the claims.

The annexed drawings and the following description set forth in detail certain mechanism embodying the invention, such disclosed means constituting but one of various mechanical forms in which the principle of the invention may be used.

In said annexed drawings, Figure 1 represents a vertical axial section of my improved controlling mechanism in combination with a suitable casing for a portable drill and a motor supported therein. Fig. 2 represents a horizontal section of such controlling mechanism, taken upon the planes indicated by the lines 2 2, Fig. 1. Fig. 3 represents a vertical section taken upon the plane indicated by the line 3 3, Figs. 1 and 2. Fig. 4 represents a vertical section taken upon the planes indicated by the lines 4 4, Fig. 2; and Fig. 5 is a diagram illustrating the circuit connections.

My invention relates to the controlling apparatus of an electrically-driven tool or machine, and I have illustrated said invention in one of its uses as particularly applied to a portable electrically-operated drill, such as is described and claimed in my prior application for United States Letters Patent upon electrically - operated portable drills, Serial No. 224,953, filed September 19, 1904.

As shown in the above-mentioned application, I provide a suitable casing A for the drill and connected mechanism, such casing having an intermediate diaphragm A' extending transversely across the same and an upper removable head or cap A² and a lateral removable portion A³, within which is inclosed

the controlling mechanism forming the subject-matter of this invention. Within the casing A and suitably secured thereto are the four pole-pieces E' of a field structure surrounding the armature E of a multipolar series-wound constant - potential electric motor, 60 suitably secured to a motor - shaft. (Not shown.) The upper removable head A² is provided with a central aperture a', having a screw-thread, and the diaphragm A' has a central aperture a² in alignment with the aperture a', and through said apertures the spindle of the drill and the feed-screw therefore are adapted to be inserted, as explained in my above-mentioned prior application. Within the diaphragm A' are suitable bearings a³, in which are journaled pintles, that carry upon their lower ends two pinions adapted to mesh with a gear - wheel (not shown) keyed upon the drill - spindle, and upon their upper ends two pinions adapted 75 to mesh with a gear - wheel (not shown) keyed upon the motor-shaft, all as is clearly shown and described in said prior application.

The electrical drills that are at present in use are not adapted to general application, in so far as I am aware, and the reason for this is as follows: It is usually desired that very rapid work be performed, and in order to accomplish this the drill must be forced to its work by some suitable manually - operated screw device. If the turning of the said feed-screw is effected by an inexperienced man, the normal proper speed of the motor is accelerated or retarded, and if the speed becomes too slow, such as when the drill is just breaking through the work, the armature not being able to revolve the drill will suddenly stop, and if the drill is not provided with fuses the machine will be immediately 90 burned out. If the drill is provided with an ordinary circuit - breaker, the machine will not always be protected, for the operator soon discovers that he can defeat the object of the circuit-breaker and prevent it from 100 operating by simply holding it down, thus causing the drill to do more work. I have sought to eliminate this trouble and provide a drill which is at all times reliable and proof against the carelessness or ignorance of an inexperienced man by providing the automatic controlling mechanism, which will now be described in detail. The machine being

series-wound and series-connected, the magnetizing force will rise with the current, and by placing a small solenoid directly on the back of the field - core and connecting the same accumulative with the field-windings I am enabled to break the current at any time that the magnetic flux of the motor has reached a predetermined quantity. Of course no action would result if the solenoid were placed elsewhere and connected so as to oppose the field-windings to which it is connected.

A handle for the drill is illustrated at B, provided with a suitable outer screw-thread and adapted to be connected to an internally-screw-threaded integral projection *a* upon the lateral portion *A*³ of the casing. An operating-sleeve C surrounds the lower portion of the handle B and is rotatably secured by means of a screw *c* to the stem *d* of an insulating semicircular switch-disk D, as plainly shown in Figs. 1 and 4, a suitable slot *d*⁴, Fig. 4, being provided in the handle B through which the screw *c* may travel when the operating-sleeve C is actuated, thus making the handle B non-rotatable. By thus making the handle B immovable and also of quite a length and removing its outer end some distance from the operating-sleeve C the drill can be carried or rolled about by means of said handle and another handle (not shown) connected with the other side of the casing without any danger of accidentally revolving or disturbing the operating-sleeve C.

As plainly shown in Fig. 1, a solenoid H is secured upon the core of one of the field-poles E' by means of a screw G, formed out of a magnetic material which is located within and under the influence of the magnetic field and assists the solenoid in pulling a screw F inwardly, which screw F serves as a cut-out magnet and forms the core of the solenoid and is adapted to be actuated when the magnetic flux of the motor has reached a predetermined quantity, such quantity being varied as is desired, since the cut-out magnet F is adjustable by being screwed through a suspension-ring *f*, as plainly shown in Figs 1, 4, and 5. Pivoted to this suspension-ring *f* by means of pins *j* is a forked magnet and switch-lever J, provided at its outer end with a shoulder *j'*, engaging with a pin *l*² when the cut-out magnet F is in its normal upward position, which pin *l*² is secured in an element J', pivoted in ears *j*², projected upwardly from an insulated base N³, supported upon the casing A. The lever J is pivoted in uprights K, also projected upwardly from the insulated base N³. A spring l tends to turn the element J' upon its pivot *l*³, but is normally prevented from so doing by the engagement of the pin *l*² with the shoulder *j'*, as plainly shown in Fig. 5. A second spring l' serves to assist the weight of the lever J in holding the shoulder *j'* to engagement with

the pin *l*². The spring l is a wound-wire spring and is adapted to throw out a knife-switch L, and thus break the circuit between the switch-poles L', as plainly shown in Fig. 5, when the cut-out magnet F is drawn within the solenoid H and the shoulder *j'* thus freed from the pin *l*². In Figs. 1 and 2 the insulating switch-disk D is shown in its full "on" position. Said switch-disk D is provided with a projection d², forming a cam-face, as clearly shown in Figs. 1, 2, 3, and 4, and when the operating-sleeve C is actuated to turn the switch-disk D to its "off" position, which would be in the direction of the arrow, Fig. 2, said cam-face d² contacts with the element J' to move the same back to its normal upright position, as shown in Fig. 5, and the pin *l*² again engages with the shoulder *j'*, so as to hold said element J' upright. The circuit is illustrated at M, Fig. 5, and within such circuit is introduced a shunt N, having a resistance N', which shunt is rendered effective as follows: Secured to the under surface of the switch-disk D is a circular short-circuiting switch N², supported upon a plurality of contact-clips n, which in turn are secured to supports n' upon the insulated base N³. When the switch-disk D is in its full off position, the circuit is of course broken and is not again made until the switch-disk has been revolved sufficiently toward its full on position to bring the short-circuiting switch N² upon the two left-hand contact-clips n, Fig. 5, which passes the current through the shunt N until the forward end of the switch N² contacts with the right-hand clip n, thus passing the full current through the circuit. By thus introducing the shunt into the circuit I obviate the danger which is present when the full current is turned on all at once. A suitable reversing-switch O' is provided, having an operating-handle O, adapted to be interlocked with the operating-sleeve C, said handle O being operative only when the sleeve C has been turned to hold the disk D in its off position. A suitable clock-spring d', Figs. 1 and 2, is provided for holding the switch-disk D in its off position when not in use.

From the above description the operation of my controlling mechanism, which is as follows, will be readily understood: The operating-sleeve C is actuated to turn the switch-disk D to its full on position, the current being applied gradually through the medium of the shunt N, and when the magnetic flux of the motor has reached a quantity which has been thought dangerous to the machine the cut-out magnet F is drawn inwardly by the solenoid H and the magnetic member G, thus releasing the pin *l*² from the shoulder *j'*, enabling the spring l to pull the element J' forwardly until it rests against the switch-disk D, carrying with it the knife-switch L, and thus breaking the current between the switch-

poles L'. By turning the switch-disk D to its off position the element J' is carried back by the cam-face d^2 of the switch-disk D and the pin l^2 engages with the shoulder j' , thus 5 by the aid of the spring l' holding the element J' in its normal position when the switch-disk D is turned back to its full on position if the magnetic flux meanwhile has settled below the quantity which has been 10 predetermined to be that at which the cut-out magnet F should be actuated. When the drill is in use, the switch-disk D is prevented from turning under the tension of the spring d' by means of a spring-clip d^3 , which 15 is detachably hooked over a screw d^4 , secured to a lug d^5 of the switch-disk D, as plainly shown in Fig. 2. When it is desired to 20 revolve the switch-disk to its off position or to allow it to be thrown to said position by the spring d' , the operating-sleeve C can be turned with sufficient force to overcome the tension of the spring-clip d^3 , and thus release the switch-disk D therefrom, as will be clearly seen.

25 Although I have shown and described the automatic starting-switch and circuit-breaker comprising my motor-controller as particularly applied to drills, still I wish it understood that it can be used upon any electrically-driven tool or machine where it is desired to provide a small, compact, and efficient controlling mechanism.

Having described my invention in detail, that which I particularly point out and distinctly claim is—

35 1. In motor-controllers, the combination with an electric motor; of a circuit for its armature connections; means for automatically breaking said circuit when the magnetic flux of the motor reaches a predetermined quantity; and a manually-operable switch-disk adapted, when it is actuated to its "off" position, to close the break in the circuit made by said automatically-operating means.

40 2. In motor-controllers, the combination with an electric motor; of a circuit for its armature connections; means for automatically breaking said circuit when the magnetic flux of the motor reaches a predetermined quantity; a manually-operable switch-disk adapted, when it is actuated to its "off" position, to close the break in the circuit made by said automatically-operating means; and a short-circuiting switch included in said circuit and rendered operative during the actuation of said switch-disk to its "on" position.

45 3. In motor-controllers, the combination with an electric motor; of a circuit for its armature connections; a solenoid included in said circuit; circuit-breaking means adapted to be operated by the inward stroke of the core of said solenoid, such inward stroke of said core being effected when the magnetic flux of the motor reaches a predetermined quantity; a manually-operable switch-disk

adapted, when it is actuated to its "off" position, to close the break in the circuit made by said circuit-breaking means; and means for effecting the outward stroke of said core.

4. In motor-controllers, the combination 70 with an electric motor; of a circuit for its armature connections; a solenoid included in said circuit; circuit-breaking means adapted to be operated by the inward stroke of the core of said solenoid, such inward stroke of 75 said core being effected when the magnetic flux of the motor reaches a predetermined quantity; a manually-operable switch-disk adapted, when it is actuated to its "off" position, to close the break in the circuit made 80 by said circuit-breaking means; means for effecting the outward stroke of said core; and a short-circuiting switch included in said circuit and rendered operative during the actuation of said switch-disk to its "on" position. 85

5. In motor - controllers, the combination 90 with an electric motor; of a circuit for its armature connections; means for automatically breaking said circuit when the magnetic 95 flux of the motor reaches a predetermined quantity; a rotatory short-circuiting switch included in said circuit; a series of fixed contact-clips supporting said switch; manually-operable switching means adapted, when they 95 are actuated to their "off" position, to close the break in the circuit made by said automatically-operating means, the actuation of said 100 manually-operable switching means effecting the rotation of said short-circuiting switch, 100 the latter contacting with said clips during the actuation of the switching means to their "on" position, so as to render said short circuit operative.

6. In motor - controllers, the combination 105 with an electric motor; of a circuit for its armature connections; means for automatically breaking said circuit when the magnetic flux of the motor reaches a predetermined quantity, including a solenoid, a core therefor, a pivoted lever connected at one end to said core, a knife-switch, and switch-poles, said knife-switch held to engagement with the other end of said lever and held to contact with said switch-poles, when said core is 110 in its outermost position; means for effecting the outward stroke of said core; and a manually-operable switch-disk adapted, when it is 115 actuated to its "off" position, to close the break in the circuit made by said automatically-operating means. 120

7. In motor - controllers, the combination 125 with an electric motor; of a circuit for its armature connections; means for automatically breaking said circuit when the magnetic flux of the motor reaches a predetermined quantity, including a solenoid, a core therefor, a pivoted lever connected at one end to said core, a knife-switch, and switch-poles, said knife-switch held to engagement with 130

the other end of said lever and held to contact with said switch-poles, when said core is in its outermost position; means for effecting the outward stroke of said core; a manually-operable switch-disk adapted, when it is actuated to its "off" position, to close the break in the circuit made by said automatically-operating means; and a short-circuiting switch included in said circuit and rendered operative during the actuation of said switch-disk to its "on" position.

8. In motor - controllers, the combination with an electric motor; of a circuit for its armature connections; means for automatically breaking said circuit when the magnetic flux of the motor reaches a predetermined quantity, including a solenoid, an adjustable core therefor, a pivoted lever connected at one end to said core, a pivoted element held to engagement with the other end of said lever, when said core is in its outermost position, two switch-poles, and a knife-switch

connected to said pivoted element and normally held by the latter to contact with said switch-poles; means for effecting the outward stroke of said core; and a manually-operable switch-disk adapted, when it is actuated to its "off" position, to close the break in the circuit made by said automatically-operating means.

9. In a portable electrically-operated drill, the combination of an electric motor provided with a suitable casing; a drill-spindle mounted in the latter; gearing connecting said motor and spindle; a manually-operable controller for said motor; and means for automatically actuating said controller to assume the "off" position when the magnetic flux of the motor reaches a predetermined quantity.

Signed by me this 23d day of May, 1905. 40
ADOLPH PEDERSEN.
